DISPENSING CAP

Noel S. Sodders, Cleveland, Ohio

Application April 27, 1945, Serial No. 590,586

1 Claim. (Cl. 222—542)

1

The present invention relates to a dispensing cap for bottles, jars and the like. More particularly the invention relates to a dispensing cap provided with a pouring spout which may be rotated to pour toward a predetermined side of a container to which the cap is attached. The provision of effective means for accomplishing these results is the general object of the invention.

Dispensing caps of the type with which the present invention is concerned, generally comprise a cap having internal threads to coact with the threads on the neck of a container, and an angularly disposed dispensing tube. A gasket is generally disposed between the cap and the top of the container neck to provide a liquid tight seal therebetween. In such caps it has been difficult to position the dispensing tube in a predetermined position relative to the container, as for instance parallel to the flattened side of a liquor flask or to a label on the container, so that the customer may readily observe the label, and at the same time maintain a liquid seal between the cap and the container.

Another object of the invention is to provide a two part pouring nozzle, one part of which provides a cap, and may be secured to the container, as by coacting threads, and the other part of which is provided with a dispensing tube and which may be rotated relative to the cap.

A further object is to provide an improved connection between two devices, such, for instance, as a dispensing tube and a container cap through which the dispensing tube projects such as will also provide a liquid seal both between the device and a container and between the cap and the dispensing tube.

Other objects of this invention will become more apparent from the following specification, reference being had to the accompanying drawings in which a preferred embodiment of the invention is illustrated. The essential features of the invention will be summarized in the claim.

In the drawings, Fig. 1 is a view of my improved dispensing cap in position on a container; Fig. 2 is a plan view of the cap; Fig. 3 is a sectional view taken through the cap and container neck, the plane of the section being indicated by the lines 3—3 on Fig. 2; and Fig. 4 is a view of the individual parts which make up the improved dispensing cap.

Referring now to the drawings, my improved dispensing cap as a whole is shown at 10 and comprises a cap member 11 and a dispensing member 12. The latter has a dispensing tube 14

5 which projects at an angle relative thereto and which has a passageway 15 extending into the interior of the member 12. A tube 16 forms a part of the member 12 and projects downwardly therefrom. This tube, as shown in Fig. 3, is in communication with the dispensing tube 14. A vent opening 17, of a restricted cross-sectional area, extends through the member 12 and also communicates with the tube 16. The tube 16 and the passageway 15 permit the fluid contents to pass from the container when it is sufficiently tipped. Preferably both the member 12 and the tube 16 are made of a plastic material and are permanently cemented together along their junction line 19.

10 The cap member 11 has a downwardly extending skirt 20 provided with internal threads 21 adapted and arranged to coact with threads 22 formed on the exterior of the container neck 23. A gasket 25 interposed between the cap 11 and the top of the container provides a liquid tight seal between the container and the cap.

15 Another feature of the present invention is the arrangement whereby the gasket 25 not only provides a seal between the cap and container but also provides a seal between the cap member 11 and the member 12. As illustrated in Fig. 3, the tube 16 of the member 12 extends downward into the container neck through an opening 26 in the top of the cap. The gasket 25 fits the tube 16 snugly and is interposed between the undersurface of the cap and an annular bead 27 integrally formed about the tube 16. As the tube 16 nearly fills the neck of the container the pressure on the gasket 25, due to the securing of the cap to the container compresses the gasket against the tube 16 and the upper surface of the bead 27 thereon, thereby providing a liquid tight seal between the tube and the cap.

20 I have found that with such construction described, the member 12 may be rotated to place the dispensing tube in any desired position relative to the container on which the spout is used. This facilitates positioning the dispensing tube, as shown in Figs. 1 and 2, in a predetermined relation to the flat side or label 30 of the container 31 regardless of the rotary movement required to tightly affix the device securely in position on the container.

25 The gasket 25 serves not only to provide a liquid seal between the component parts of the device and between the device and the container but in addition thereto it serves to retain the member 12 in position on the cap. To this end the bead 27 is positioned on the tube 16 so that

when the latter is positioned on the cap the upper surface of the bead is spaced from the under side of the cap a distance substantially equal to the thickness of the gasket. Thus when the gasket is positioned about the tube 16 it serves to retain the member 12 in position on the cap.

The gasket 25 is preferably made of a resilient plastic material although it may be made of rubber or other somewhat compressible material having sufficient strength and not liable to contaminate the contents of the container.

When the cap is tightened into position on a container the pressure between the cap and the top of the container results in pressure of the gasket toward the tube 16 and the bead 27 thereby drawing the shoulder 34 of the member 12 tightly into contact with the upper surface of the cap. This construction is such that application of the device to the container increases the effectiveness of the gasket 25 in retaining the parts of the device together.

It will be apparent from the foregoing specification that I have provided a pouring spout which may be easily manufactured and assembled and which is so arranged that the dispensing tube 25 thereof may be turned to any desired position relative to the container on which the device is used. It will be also understood that while I have described my invention in connection with a pouring spout for a bottle the invention is not limited to such specific application.

I claim:

A pouring spout comprising a cap having an internally threaded skirt to coact with external threads on the neck of a container to secure the cap in position thereon, said cap having an opening therethrough, an elongated hollow

member rotatably mounted in said opening and having an open ended portion adapted to extend downward into the neck of the container and a portion above the cap, said last named portion being provided with an angularly projecting pouring spout and having a shoulder in engagement with the top of the cap, an annular bead on said downward extending portion spaced from the bottom wall of said cap and having an external diameter smaller than the internal diameter of the opening in the cap, and a resilient annular washer encircling said downward extending portion and positioned between the inner face of the cap and the upper portion of said bead and acting to retain said member and cap together as a unit at all times, and acting as a seal between the container and cap when the cap is in position on a container, and wherein said member may be rotated to adjust the position of said spout while maintaining the seal between the cap and the container and the seal between said member and the cap.
